COLLAPSIBLE VIAL

Blair M. Drake, Berlin W. Kagy, and Richard W. Hall,
Tiffin, Ohio

Application November 10, 1954, Serial No. 33,050

Term of patent 14 years

(Cl. D58—17)

Fig. 1.

Fig. 2.

Fig. 3.

Fig. 4.

Fig. 5.

Fig. 6.

Fig. 7.

Figure 1 is a front elevational view of a collapsible vial showing our new design.

Figure 2 is a side elevational view.

Figure 3 is a top plan view of the vial shown in Figure 1.

Figure 4 is a bottom plan view of the vial shown in Figure 1.

Figure 5 is an enlarged sectional view taken along the line 5—5 of Figure 1 and in the direction of the arrows.

Figure 6 is an enlarged sectional view taken along the line 6—6 of Figure 2 and in the direction of the arrows.

Figure 7 is an enlarged sectional view taken along the line 7—7 of Figure 2 and in the direction of the arrows.

We claim:

The ornamental design for a collapsible vial, substantially as shown.
